UNITED STATES PATENT OFFICE.

THEODORE A. DOUGHTY, OF WOODSTOCK, ILLINOIS.

STOVE.

SPECIFICATION forming part of Letters Patent No. 777,187, dated December 13, 1904.

Application filed February 26, 1904. Serial No. 195,371. (No model.)

To all whom it may concern:

Be it known that I, THEODORE A. DOUGHTY, a citizen of the United States of America, residing at Woodstock, in the county of McHenry 5 and State of Illinois, have invented certain new and useful Improvements in Stoves, of which the following is a specification.

My invention relates to certain new and useful improvements in stoves; and its object is 10 to produce a device of this class which shall have certain advantages, which will appear more fully and at large in the course of this specification.

To this end my invention consists in certain 15 novel features of construction, which are clearly illustrated in the accompanying drawings and described in this specification.

In the aforesaid drawings, Figure 1 is a central vertical section through my improved 20 stove. Fig. 2 is a horizontal section in the line 2 2 of Fig. 1. Fig. 3 is a horizontal section in the line 3 3 of Fig. 1. Fig. 4 is a horizontal section in the line 4 4 of Fig. 1, and Fig. 25 is an under plan of a portion of the bottom of the stove.

Referring to the drawings, A is the casing of my improved stove, the said casing having in the preferred form of construction a fire-pot a , which is separated by a slight distance 30 from the wall of the casing.

The stove is provided with a magazine a' for the entrance of coal at the top, a door a^2 above the fire-pot a , and a door a^3 in the ash-pit below the fire-pot. Below the fire-pot a is an annular chamber B, which lies against the wall 35 of the casing and is provided with perforations b at its bottom. The form of this annular chamber will be clearly understood by reference to the drawings. It will be seen that it 40 is in the preferred form semicircular in vertical section, so that the upper and central part shields the perforations at the bottom from the ashes which might otherwise fall into them. This annular chamber B has a gap at its forward end to leave room for the door a^3 and is 45 therefore not perfectly continuous around the lower end of the stove. At the rear of the casing A is a flue C, the lower end of which communicates with the rear of the annular chamber B and which is provided near the top of

the casing with a cross-flue C', entering the upper part of the casing A.

The bottom of the casing A is provided with two perforations, through which pass pipes D, said pipes extending upward into the annular chamber B on opposite sides of the center and extending through the same, as illustrated in Fig. 3, these pipes being continued back into the flue C, turned upward therein, and carried back through the cross-flue C' into 60 the upper part of the stove, the said pipes being provided with curved ends D', which surround the magazine a' and are perforated, as shown. By means of this construction air can enter the lower ends of the pipe D from below 65 the stove, pass along the pipes D, through the annular chamber B, up the flue C, back into the body of the stove, and thence down to the fire-pot, as illustrated by the arrows in the drawings. The fire-pot is preferably constructed 70 with vertical slots in its wall, and an annular space is provided between the fire-pot and the casing of the stove, so that the downdraft may pass around the fire besides passing through it. After passing by the fire-pot the air can 75 enter the perforations b in the chamber B, pass again therethrough around the pipes D, and pass up into the flue C into the chimney. In this way an efficient downdraft-stove is provided, which has the particular advantage 80 that the fresh air before it enters the interior of the stove passes in tubes through the exhaust-flue and is heated by contact with the products of combustion.

In order to control the drafts of my improved stove, three dampers are provided. One damper, E, Fig. 5, controls the amount of air passing through the pipes D. This damper, it will be seen, consists in the preferred form of two circular plates e , pivoted to the 85 bottom of the stove, the said plates being connected by a cross-bar e' . A push-lever E' is provided on the bottom of the stove, the rear end of this push-lever being bent downward at e^2 to form a cam-surface engaging with the 90 cross-bar e' , so that as the push-lever E' is pushed in the cross-bar will be moved up, thus swinging the plates e against the bottom of the stove and closing the ends of the pipes D. The second damper is indicated by F,

and this damper when closed greatly contracts the capacity of the flue C. The third damper is indicated at G, and this damper closes the cross-flue C'.

- 5 Occasionally, as in starting a fire, it is desirable to have a stronger draft than can be obtained with the arrangement of air-passages thus far described, and in such case the damper F is closed, the damper G is opened to 10 establish direct communication of the interior of the stove with the chimney, and the lower door a^3 or a draft therein is opened. In this case the air passes in through the lower door or draft, through the fire-pot, and directly up through the body of the stove and 15 through the cross-flue C' into the chimney. In this way a stove of ordinary operation is obtained which can be shifted to a downdraft-stove with little or no difficulty.
- 20 I realize that considerable variation is possible in the details of this construction without departing from the spirit of the invention,

and I therefore do not intend to limit myself to the specific form herein shown and described.

25

I claim as new and desire to secure by Letters Patent—

In a device of the class described, the combination with a suitable casing and fire-pot therein, of a perforated annular chamber with- 30 in the casing below the fire-pot, an eduction-flue in communication with said annular chamber, an intake-pipe extending through the bottom of the casing into said annular chamber, thence up the eduction-flue and thence 35 into the upper part of the casing.

In witness whereof I have signed the above application for Letters Patent, at Woodstock, in the county of McHenry and State of Illinois, this 22d day of February, A. D. 1904. 40

THEODORE A. DOUGHTY.
